(57) **CLAIM**

The ornamental design for a display screen or portion thereof with graphical user interface as shown and described.

DESCRIPTION

FIG. 1 is a front view of a display screen or portion thereof with graphical user interface showing our new design; FIG. 2 is a front view of a second embodiment thereof; and, FIG. 3 is a front view of a third embodiment thereof. The outermost dot-dash line rectangle illustrates a display screen or portion thereof and forms no part of the claimed design. The other broken lines in the drawings illustrate portions of the graphical user interface that form no part of the claimed design.
